UNITED STATES PATENT OFFICE.

JAMES M. S. CARROLL, OF WESTMOUNT, QUEBEC, CANADA.

STRAP-TRIMMING MACHINE.

1,157,844.

Specification of Letters Patent. Patented Oct. 26, 1915.

Application filed January 25, 1915. Serial No. 4,235.

To all whom it may concern:

Be it known that I, JAMES M. S. CARROLL, of the city of Westmount, in the Province of Quebec, Dominion of Canada, have invented 5 certain new and useful Improvements in Strap-Trimming Machines; and I do hereby declare that the following is a full, clear, and exact description of the same.

My invention relates particularly to machines for trimming and more particularly for concaving the deckle straps used on paper making machines for cutting the web to predetermined width; and the object thereof is to enable the straps to have their 15 corners sharpened without sending them from the paper mill.

The invention may be said briefly to consist of a pair of machine frames each having mounted therein a guide wheel of suitable width to accommodate various sizes of straps, a third and intermediate wheel being located between these guide wheels and adapted to take up the slack in the strap, an adjustable flange being provided to guide 20 the strap relatively to a grinding wheel suitably mounted. For full comprehension, however, of my invention, reference must be had to the accompanying drawings forming a part of this specification in which similar 25 reference characters indicate the same parts, and wherein:

Figure 1 illustrates my improved machine in side elevation; Fig. 2 is a detail sectional view drawn to an enlarged scale and illustrating the strap trimming roller in bearing 35 relation with the strap; Fig. 3 is a detail horizontal sectional view taken on line A B Fig. 2; and Fig. 4 is a diagrammatic view of the complete machine drawn to a reduced 40 scale.

The machine is divided into three sections each mounted upon an independent frame, such frames being indicated at *a*, *b* and *c*. The section *a* comprises in addition to its 45 frame a pair of shafts 2 and 3, the shaft 3 being mounted in bearings 4 fixed to the frame and the shaft 2 in a bearing 5 adjustable on the frame relatively to the shaft 3. The shaft 3 carries a guide-wheel consisting 50 of a rim of sufficient width to accommodate straps of different widths. As these deckle straps are usually of substantially square cross-section sufficient space is provided for them between the rim 6 and frame *b* to 55 permit a guiding device 7 to be mounted upon the latter and adjusted to meet differ-

ent widths of belt. This guiding device consists of a member of angular form slotted as at 8 to fit over a screw-threaded stud carried rigidly by the frame *b*, a butterfly 60 nut 9 serving to clamp the guide in the required position to locate the belt centrally relatively to the grinding wheel, the position of this guide, of course, depending upon the width of the belt to be ground. 65

The shaft 2 carries an emery wheel 15 preferably formed with a slightly convex perimeter and equal in length to the greatest width of strap to be ground. The bearing 5 is adjusted relatively to the guide wheel 70 and in a radial direction with relation thereto by means of a screw 16 threaded through a tapped boring in a bearing 17. In order to enable this emery wheel to be adjusted to bring its center in juxtaposition with the 75 center circumferential line of the belt to be ground the bearings 5 and 17 are mounted upon a slide 20 adjusted by means of screws 21. The guide wheel and emery wheel are driven by separate power shafts 24 and 25, 80 the emery wheel having a higher speed than the guide wheel and being operated preferably by its own motor 29. The frame of this section *a* of this machine is preferably fixed and the section *c* preferably adjustable relatively thereto on a base 26 to which it is secured in any position to which it may be adjusted by clamping bolts 27. This section *c* of the machine comprises besides its carrying frame a shaft 30 upon which is 85 mounted a guide wheel of the same construction as the guide wheel 6 in order to accommodate different sizes of straps. 90

The slack in the strap is taken up by a roller 35 mounted in vertically adjustable 95 bearings 28 on its frame which in turn rests on a base 36 upon which it is adjusted relatively to the frame *a* and is fastened in any position to which it may be adjusted by clamping bolts 27. 100

The guide wheels may be carried in trunnions supported in any other than described without departing from the spirit of this invention.

Operation: In the operation of my improved deckle strap trimming machine, the strap is slipped on to the rims 6. The section *c* of the machine is then adjusted relatively to the section *a* to make the strap taut, the slack being taken up by the adjusting roller 35 upwardly to the required extent. The emery wheel is then adjusted 105 110

to proper position with relation to the strap. The machine may then be started and during operation the emery wheel is fed slowly to cut into the strap the distance necessary to form sharp corners on the latter. In order to remove the strap the section *c* of the machine is moved toward the section *a*, thus slackening the strap and allowing it to be removed.

10 What I claim is as follows:

1. In a deckle strap trimming machine the combination with an emery wheel having a convex surface, of a pair of strap carrying wheels and adjustable means whereby the belt is guided, substantially as described.
- 15 2. In a deckle strap trimming machine the combination with a guide wheel and an independent frame, of an angle iron guide mounted adjustably upon the said independent frame in position to guide the strap operated upon, substantially as described.

3. In a deckle strap trimming machine the combination with a pair of guide wheels adapted to carry a strap, one being stationary and the other adjustable relatively thereto, and means for driving said stationary guide wheel, of an emery wheel having a convex surface and adjustable to and from said stationary guide wheel for the purpose of operating upon said strap, and vertically 20 adjustable means located intermediate of said guide wheels adapted to bear upon said strap for the purpose of taking up any slack therein.

In testimony whereof I have signed my 35 name to this specification in the presence of two witnesses.

JAMES M. S. CARROLL.
